(57) **CLAIM**

The ornamental design for a hose pot and planter, as shown and described.

DESCRIPTION

FIG. 1 is a top perspective view of the hose pot and planter of the present invention;

FIG. 2 is a front view, the rear view being a mirror image thereof;

FIG. 3 is a left side view, the right side view being a mirror image thereof;

FIG. 4 is a top view thereof; and,

FIG. 5 is a bottom view thereof.

The portions of the planter illustrated in broken lines in FIGS. 1, 4, and 5 are included for the purpose of showing parts that form no part of the claimed design.
